No. 703,378.

Patented July 1, 1902.

S. BLAUSTEIN.
WINDOW SHADE HANGER.

(Application filed Dec. 18, 1901.)

(No Model.)

UNITED STATES PATENT OFFICE.

SOLOMON BLAUSTEIN, OF BALTIMORE, MARYLAND.

WINDOW-SHADE HANGER.

SPECIFICATION forming part of Letters Patent No. 703,378, dated July 1, 1902.

Application filed December 18, 1901. Serial No. 86,425. (No model.)

To all whom it may concern:

Be it known that I, SOLOMON BLAUSTEIN, a citizen of the United States, residing at Baltimore, in the State of Maryland, have invented 5 a new and useful Window-Shade Hanger, of which the following is a specification.

The invention relates to improvements in window-shade hangers.

The object of the present invention is to 10 improve the construction of window-shade hangers and to provide a simple, inexpensive, and efficient one adapted to support a spring-roller curtain-shade and capable of raising and lowering the same bodily to 15 range the window-shade at any portion of a window and to space the same from the top of the window to provide ventilation and light at the upper portion thereof.

The invention consists in the construction 20 and novel combination and arrangement of parts hereinafter fully described, illustrated in the accompanying drawings, and pointed out in the claims hereto appended.

In the drawings, Figure 1 is an elevation 25 of a window-shade hanger constructed in accordance with this invention. Fig. 2 is a vertical sectional view of the same. Fig. 3 is a perspective view of the bracket or bar. Fig. 4 is an enlarged vertical sectional view 30 of one end of the bracket or bar. Fig. 5 is an enlarged detail perspective view of one end of the transverse bar or bracket.

Like numerals of reference designate corresponding parts in all the figures of the drawings.

1 designates a transversely-disposed horizontal curtain-shade-supporting bar provided at the ends with forwardly or outwardly projecting casings 2, open at the 35 front, and provided at the inner side walls with extensions 3 and 4, having bearing-openings adapted to receive the journals of a spring-roller of a curtain-shade 5. The opening of the extension 3 is formed by a slot 40 or recess and receives the squared journal, which is connected with the spring of the spring-roller in the usual manner, and the other extension 4 is provided with a circular opening to receive the other journal of the 45 spring-roller. By this construction a spring-roller curtain-shade is readily mounted on and removed from the transverse bar or

55 bracket. The casings may be constructed in any suitable manner and are adapted to receive grooved antifriction-rollers 6. The outer walls of the casing are preferably formed by extending the ends of the bar outward at right angles, and the inner and top walls of the casing are formed integral with each other and are riveted or otherwise secured to the transverse bar; but the casings 60 may be constructed in any other suitable manner.

The grooved rollers, which are arranged 65 within the end casings of the transverse bar, are mounted on suitable spindles; but they may be journaled in any other suitable manner, and the top and bottom walls of the end casings are provided with apertures 7, through which pass guides 8, mounted on the window-frame at opposite sides thereof and receiving the end rollers or wheels. The end guides, 70 which may consist of stout wire, rods, barded wire, or other similar construction, also receive eyes 9, extending horizontally from 75 the bottom of the curtain-shade at opposite sides thereof and preferably mounted on the wooden stick which is usually arranged in a casing at the bottom of the window-shade. These eyes prevent the curtain-shade from 80 moving laterally and from rolling up unevenly on the shade-roller, and they also prevent the side edges of the curtain-shade from becoming worn or otherwise injured by uneven rolling. The end casings of the transverse bar or bracket are also open at the 85 back, and the end rollers or wheels project beyond the rear or inner face of the transverse bar; but the rollers or wheels may be mounted entirely within the end casings, if desired.

The transverse bar is provided with a central opening 10, and it has a central casing 11 mounted on it and arranged at the inner or rear face of the bar at the central opening 95 10. This bracket-casing 11, which is open at the back, may be constructed in any other suitable manner, and it is provided at the top and bottom walls with apertures 12, and it receives a central antifriction roller or 100 wheel 6, which is grooved to engage a central guide 13. The central guide, which may be constructed of any suitable material, like the side guides 8, passes through the upper

and lower apertures of the central casing and is arranged in the groove of the central roller or wheel. The central guide extends from the top to the bottom of the window-frame, 5 as clearly shown in Fig. 1, and it assists in guiding the transverse bracket or bar.

The transverse bar or bracket is supported by side cords 14, depending from side pulleys 15 and secured to the bar or bracket near the 10 ends thereof, preferably by being tied to rings 16, which are linked into perforations of the bar or bracket; but the depending portions of the side cords may be secured to the bracket or bar in any other suitable manner. The 15 side cords or branches 14 extend inward horizontally from the side pulleys 15 to a pair of central pulleys 17, whereby they are connected with a central cord or branch 18, and the latter extends downward to a bottom roller 20 19 and is coiled around the same. The central cord then passes upward from the bottom roller and is secured to a depending portion of the bracket. The side cords or branches may be connected with a central cord or 25 branch in any suitable manner, and the crotch formed by the inner ends of the side cords is adapted to engage the central pulleys to form a stop for limiting the downward movement of the bracket or bar to prevent the same 30 from being drawn down to the extreme bottom of the window-frame. The bottom roller 19 is mounted in suitable bearing brackets or supports 20, and in order to cause the central cord to roll up smoothly on the bottom roller 35 19 an upper parallel roller 21 is also mounted between the brackets 20; but this roller may be omitted, if desired. The space between the two rollers 19 and 21 is about equal to the thickness of the curtain-cord, which will therefore 40 be prevented from overlapping and rolling up unevenly on the bottom roller. As the central cord unwinds from one side of the bottom roller it will wind up on the other side, and by keeping the cord smooth on the bottom roller 45 in this manner it will prevent any variation in the tension of the cord. Any suitable means may, if desired, be employed for locking the bottom roller against movement to secure the curtain at any desired adjustment. The depending portion 22 of the bracket to which 50 the central cord is secured may be constructed of wire or any other suitable material, as illustrated in the accompanying drawings, and it is provided with an eye or opening for 55 the reception of the end of the central cord.

It will be seen that the window-shade hanger is exceedingly simple and inexpensive

in construction, that it is strong and durable, and that it is adapted to receive an ordinary spring-roller and is capable of raising and lowering a window-shade bodily to arrange the same at any portion of a window and to provide ventilation and light above the curtain or shade. 60

What I claim is— 65

1. A device of the class described comprising central and side guides, a bracket or bar provided with central and side casings having top and bottom apertures receiving the guides, rollers or wheels mounted within the casings 70 and arranged to run on the guides, means for raising and lowering the bracket or bar, and a window-shade mounted on the bracket or bar, substantially as described. 75

2. A device of the class described comprising a bracket or bar, side pulleys, central pulleys, a central branch or cord and the side branches or cords arranged on the said pulleys and connected at their outer ends with the bracket or bar and at their inner ends with the central cord or branch, the inner ends 80 forming a crotch arranged to engage the central pulleys, substantially as described. 85

3. A device of the class described comprising the central and side pulleys designed to be arranged at the top of a window, a bottom roller, a transverse bar or bracket, the side cords or branches arranged on the pulleys and forming a crotch for engaging the central pulleys and connected at their outer ends to the bracket or bar, and the central branch or cord wound around the bottom roller and connected with the bracket or bar and with the inner ends of the side cords or branches, substantially as described. 90 95

4. A device of the class described comprising the central and side pulleys designed to be mounted at the top of a window, the bottom rollers 19 and 21 designed to be mounted at the bottom of the window, a transverse bar or bracket, the side cords arranged on the central and side pulleys and forming a crotch and connected with the bracket or bar, and the central cord or branch wound around the roller 19 and connected with the bracket or bar and with the inner ends of the side cords or branches, substantially as described. 100 105

In testimony that I claim the foregoing as my own I have hereto affixed my signature in the presence of two witnesses.

SOLOMON BLAUSTEIN.
